A. LA MOTTE.

BLASTING CAP.

APPLICATION FILED SEPT. 29, 1920.

Patented Aug. 1, 1922.

Inventor

Arthur La Motte,
By his attorney
F.R. Squair

UNITED STATES PATENT OFFICE.

ARTHUR LA MOTTE, OF WILMINGTON, DELAWARE, ASSIGNOR TO E. I. DU PONT DE NEMOURS & COMPANY, OF WILMINGTON, DELAWARE, A CORPORATION OF DELAWARE.

BLASTING CAP.

1,424,204.

Specification of Letters Patent. Patented Aug. 1, 1922.

Application filed September 29, 1920. Serial No. 413,548.

To all whom it may concern:

Be it known that I, ARTHUR LA MOTTE, a citizen of the United States, and a resident of Wilmington, in the county of New Castle 5 and State of Delaware, have invented a certain new and useful Blasting Cap, of which the following is a specification.

This invention relates to blasting caps which contain a secondary detonating compound, such as tetryl, in addition to a priming charge such as mercury fulminate.

A preferred embodiment of my invention is illustrated in the accompanying drawing, which shows a longitudinal section through 15 the axis of a cylindrical blasting cap.

With reference to the drawing, the cap comprises a cylinder 1, closed at the lower end, and holding therein a tightly fitting cylinder 2. The cylinder, or as I shall hereinafter designate it, reinforcing capsule, 2, is open at both ends, but is provided at its upper end with an inwardly extending flange 3, leaving but a relatively small, or restricted, opening 4 at the upper end.

25 In the manufacture of the ordinary blasting caps of the type above described, first a secondary detonating compound and then a priming charge comprising fulminate, is introduced into the cylinder 1, the capsule 2 inserted, and then the capsule and the charge thereunder subjected to high pressure. The resulting cap has in the lower part 5 a secondary detonating compound such as trinitrotoluene extending up, say, to the level 6, 30 and above that, and up to the level of the opening 4, a priming charge 7.

35 My invention consists chiefly in superimposing a layer of a readily ignitable material 8, extending from the flange 3 to the level 9 or to any other suitable level.

40 As above indicated, blasting caps have in the past been manufactured which contain a so-called secondary detonating compound, such as trinitrotoluene, picric acid, tetryl and nitrated ivory nut, all of which, 45 however, require to be fired by a primer of mercury fulminate. In order to obtain a satisfactory blasting cap of this type, it has been necessary to use a reinforcing capsule, 50 for unless such a capsule is used, a very large weight of a priming charge of mercury fulminate is required, so large, in fact, that a blasting cap of this type is not economical to manufacture.

It will be noted that the flange 3 of the 55 capsule covers a portion of the top surface of the fulminate. This presents some disadvantages in that it offers a smaller area of fulminate to the spark or flame from the fuse. Instances have been known where 60 safety fuse, when cut at an angle, has doubled over and prevented the spark from igniting the restricted area of fulminate. The present invention is designed to overcome this difficulty by superimposing a layer of 65 a readily ignited material above the capsule in a cap of the type described.

The choice of a satisfactory material for 70 this top layer is very wide, as any material that ignites readily and burns or explodes quickly will serve the purpose. Thus, for 75 example, fulminate itself, guncotton, nitro-starch, nitrated ivory nut and black powder have all been used successfully in testing my invention. It is desirable, however, if possible, to use a material which is as non-hygroscopic as possible. The most successful material of all those tried is a modified 80 black powder in which a portion (for example, 50%) of the sulphur of ordinary black powder is replaced by antimony sulphide. Actual tests have shown that caps containing, for instance, a base charge of nitrated ivory nut, a priming charge of mercury fulminate and potassium chlorate, covered 85 by a reinforcing capsule and an igniting charge of modified black powder withstand the adverse conditions of storage in damp locations for a much longer time than ordinary blasting caps composed of mercury fulminate and potassium chlorate.

90 It will be understood that blasting caps possessing the specially prepared ignitable surface above described may be changed in various ways without departing from my invention, which consists essentially in providing an ignitable surface larger than the area of the opening in the reinforcing capsule.

I claim:

1. As a new article of manufacture, a 100 blasting cap containing a secondary detonating compound and a priming charge at least partly enclosed by a reinforcing capsule provided at its upper end with a restricted opening, and a readily ignitable material 105 comprising potassium nitrate disposed over said opening and having an exposed surface larger than the area of said opening.

2. As a new article of manufacture, a blasting cap containing a secondary detonating compound and a priming charge at least partly enclosed by a reinforcing capsule, said capsule having at its upper end an inwardly extending flange forming a restricted opening, and a layer of an easily ignitable material comprising a black powder composition covering both said flange and said opening.

3. A blasting cap of the kind described in

claim 1, in which the easily ignitable top layer is a modified black powder in which less than half of the sulphur has been replaced by antimony sulphide. 15

4. A blasting cap of the kind described in claim 1, in which the easily ignitable material above the reinforcing capsule is also non-hygrosopic.

In testimony whereof I affix my signature.

ARTHUR LA MOTTE.
